Patented Jan. 2, 1973

225,750

ACOUSTIC COUPLER

Joseph P. Marsalka, 4211 Woodbridge 43221, and
Richard D. Fretwell, 1891 Willoway Circle N. 43220,
both of Columbus, Ohio

Continuation-in-part of design application Ser. No.
22,893, May 8, 1970. This application June 17,
1971, Ser. No. 154,268

Term of patent 7 years

Int. Cl. D14—03

U.S. Cl. D26—14

FIG. 1 is a view in perspective of an acoustic coupler embodying our new design;

FIG. 2 is a view in side elevation of the coupler illustrated in FIG. 1;

FIG. 3 is a view in rear elevation of the coupler illustrated in FIG. 1;

FIG. 4 is a top plan view of the coupler illustrated in FIG. 1; and

FIG. 5 is a view in side elevation of the opposite side of the coupler illustrated in FIG. 2.

This is a continuation-in-part of design application Ser. No. 22,893, filed May 8, 1970, and now abandoned.

We claim:

The ornamental design for an acoustic coupler, as shown and described.
